UNITED STATES PATENT OFFICE.

GEORG BERNHARD ULRICHS, OF HOBOKEN, NEW JERSEY.

CHAIR-FAN.

SPECIFICATION forming part of Letters Patent No. 394,229, dated December 11, 1888.

Application filed April 30, 1888. Serial No. 272,307. (No model.)

To all whom it may concern:

Be it known that I, GEORG BERNHARD ULRICHS, a resident of Hoboken, Hudson county, New Jersey, have invented an Improved 5 Chair-Fan, of which the following is a specification.

The object of my invention is to provide a fan-operating mechanism for attachment to a chair, which mechanism and fan will be actuated by the weight of a person sitting in the chair.

The invention consists in the details of improvement and the combinations of parts that will be more fully hereinafter set forth.

15 Reference is to be had to the accompanying drawings, forming part of this specification, in which—

Figure 1 is a side elevation of a chair provided with my improvements. Fig. 2 is a 20 horizontal sectional view of the same on the line *c c*, Fig. 1. Fig. 3 is a vertical cross-section enlarged, taken on the line *k k*, Fig. 1, through a portion of the fan-operating mechanism. Fig. 4 is a similar view of a modification. Fig. 5 is a horizontal longitudinal sectional view, also enlarged, of a portion of the lever that carries the driving-rack. Fig. 6 is a vertical cross-section of a portion of the chair taken on the line *c' c'*, Fig. 1; and Fig. 7 25 is a side elevation, enlarged, of the fan-carrying shaft and its driving-gear, looking from the side of the chair opposite that shown in Fig. 1.

In the accompanying drawings, the letter A represents a chair, which may be of suitable construction.

B is the seat of the chair, which is vertically movable, and is preferably hinged to the chair at one side, as at *a*, or pivoted in or near the middle.

b is a leaf hinged to one of the side rails, *b*², of the chair-bottom, as shown in Fig. 6. The leaf *b* carries a lever, *d*, that is jointed to a pendent arm, *e*, which is supported by a lever, *g*, as hereinafter described.

f is a leaf similar to the leaf *b*, and hinged to a rail, *b*², opposite to the leaf *b*. The free end of the leaf *f* rests upon the lever *d*; but the leaf *f* may be dispensed with, if desired. The chair-seat B rests upon the leaf *b*, and when weighted acts to depress the lever *d*; but, if preferred, the lever *d*, or even the arm

e, could be secured directly to the swinging seat B and both leaves *b* and *f* dispensed with.

55 The lower end of the arm *e* rests upon a lever, *g*, that is pivoted to the chair-leg *i* or to a projection, *h*, thereon. The upper edge of the lever *g* is preferably notched, as shown, to receive the end of the arm *e*. The chair-leg *i* carries another lug, *j*, having a pin, *l*, that passes through a slot in a lever, *m*, which lever *m* carries a pin, *n*, that projects through a slot in the lever *g*, as clearly shown in Fig. 5; but the pin *n* may be attached to the lever 60 *g* and pass through a slot in the lever *m*, and in like manner the pin *l* may be attached to the lever *m* and pass through a slot in the lug *j*. By this means, as the lever *g* is depressed by the seat B acting through the lever 65 *d* and arm *e*, the lever *m* will also be depressed and at the same time permitted longitudinal movement. *m*⁴ is a spring secured to the lever *m* and at its opposite end to the chair A, which spring acts to elevate the lever *m*.

70 75 To the free end of the lever *m* is pivotally secured a vertical rack, *p*, which is guided on a post or vertical rod, *q*, that is securely held in the chair, as shown in Fig. 1. The most convenient manner of guiding the rack *p* is 80 by securing it to a tube, *o*, that embraces the rod *q*.

The rack *p* meshes with a pinion, *r*, that is loose on a shaft, *s*, which shaft is carried by a 85 box, *t*, secured to one of the chair-legs, as *u*. Secured to the pinion *r* is a ratchet-wheel, *v*, that is engaged by a pawl, *w*, carried by a toothed wheel, *x*, rigidly secured to the shaft *s*.

The gear-wheel *x* meshes with a pinion, *y*, secured to a shaft, *z*, that is journaled at one 90 end in the box *t*, and at its opposite end in a similar box, *a*², that is carried by the chair-leg *d*².

*e*² is a gear-wheel that is carried by the shaft *z*, and that meshes with a gear-wheel, *f*², that 95 is carried by an upright shaft, *g*², which is journaled on a plate, *h*², that lies along the side of the box *a*², and is held there by the shaft *z*. The gear-wheel *f*² passes through a slot in the plate *h*², and also through an opening in the side of the box *a*², as clearly shown 100 in Fig. 7. The shaft *g*² is secured to a vertical shaft, *i*², by a connecting-sleeve, *i*⁴, on the upper end of which shaft *i*² is secured the

fan D, which is of such construction as to deliver air when rotating; but the shafts i^2 and i^3 could be in one piece, if desired.

The fan D is adapted to be moved toward and from the occupant of the chair around the pivot Z of the plate h^2 , and for the purpose of guiding and steadyng its shaft i^2 , I provide a slotted guide-rail, j^2 , which is secured to the chair-frame. The guide-rail j^2 has a longitudinal slot, in which a sliding block, l^2 , is received. This block l^2 carries a spring, m^2 , that bears upon the guide-rail j^2 , so as to hold the block l^2 in the desired position. The shaft i^2 passes through an aperture in the block l^2 , and through a small block or plate, o^2 , that is swiveled in said aperture. With this construction, as the block l^2 is moved along the guide-rail j^2 , the plate o^2 will turn on its pivot, so that the shaft i^2 will be free to turn in its bearings in all its positions. As the block l^2 is moved along the guide-rail j^2 , the shaft i^2 will turn the plate h^2 on its pivot Z to follow the direction of the shaft. As the plate h^2 thus turns, the wheels $e^2 f^2$ will still remain in gear.

My improved chair-fan operates as follows: Supposing the rack p to be elevated and the swinging seat B to rest upon the leaves $b f$, a person now sits down upon the seat B. His weight, acting upon the sleeve o and rack p through the lever d , arm e , and levers $g m$, depresses the rack p . As the rack p descends, it turns the pinion r , and thereby the wheel x , pinion y , shaft z , and wheels $e^2 f^2$, shafts $g^2 i^2$, and thereby the fan D. When the rack has reached its lowest point, or at any other time, and the occupant of the chair rises or removes his weight from the arm e , the spring m^4 , acting on the lever m , elevates the rack p , ready to again descend, the ratchet-wheel v and pawl w permitting the pinion r to turn as the rack rises without turning the wheel x . As the rack p and sleeve o descend in a straight line on the rod q , the lever m must necessarily advance, which movement is permitted by the pins $l n$ passing through the slots in the levers $g m$, as heretofore described.

In the modification shown in Fig. 4 the pinion r is rigid with the wheel x , and the ratchet v and pawl w are dispensed with. With this construction the weight on the seat B will act to turn the fan D through the connected gearing in one direction, while the spring m^4 , when the weight is removed from the seat, will act to raise the rack p , and thereby turn the pinion r , wheel x , and connected gearing in the reverse direction, thereby also turning the fan D. Thus the fan is turned in whatever direction the rack p moves.

It is evident that the fan D and the parts connecting it with the shaft z could be on the same side of the chair as the rack p , or it could be on any other side of the chair desired.

The arm e may rest directly on the lever m ,

in which case the lever g could be dispensed with, one pivotal connection of the lever m being slotted.

Having now described my invention, what I claim is—

1. The combination, with a movable chair-seat, of the arm e , depending from said seat, lever m below the seat, means, substantially as described, for connecting the arm e with the lever m , rack p , pivotally carried by the lever m , a guide for said rack, pinion r in gear with said rack, gear-wheel x , driven by the pinion r , and the fan D, geared with said wheel x , substantially as described.

2. The combination, with a movable chair-seat, of the arm e , depending from said seat, levers m and g , having a pin and slot, respectively, to receive said pin, rack p , carried by the lever m , a guide for said rack, pinion r in gear with said rack, gear-wheel x , driven by the pinion r , engaging gear-wheel x , shaft z , carrying pinion y , gear-wheels $e^2 f^2$, shaft i^2 , driven by the wheel f^2 , and fan D, carried by the shaft i^2 , substantially as described.

3. The combination, with the chair and its seat, of the arm e , lever g , lever m , having pin n , rack p , pin l , and rod q , for guiding said rack, the lever g having a slot that receives the pin n , and the lever m having a slot that receives the pin l , carried by the chair-leg, all for converting the reciprocating motion of the seat into rectilinear reciprocating motion of the rack, substantially as described.

4. The shaft z and gear-wheel e^2 thereon, combined with the swiveled plate h^2 , that is hung on the shaft z , gear-wheel f^2 , hung in the plate h^2 and engaging the wheel e^2 , shaft i^2 , driven by the wheel f^2 , and fan D, carried by the shaft i^2 , substantially as described.

5. The shaft z , swiveled plate h^2 , hung thereon, gear-wheel e^2 , carried by said shaft, gear-wheel f^2 , hung in the plate h^2 , and shaft i^2 , connected with the wheel f^2 , combined with the slotted guide-rail j^2 , block l^2 in said slot, and block o^2 , swiveled in the block l^2 , the shaft i^2 passing through the block o^2 , substantially as described.

6. The chair-seat B, combined with the arm e , depending from said seat, levers $m g$, having a pin and a slot, respectively, to receive said pin, rack p , carried by the lever m , a guide for said rack, fan D, and intermediate mechanism, substantially as described, between the rack p and said fan D, substantially as herein described, for turning said fan by means of said rack, and with the spring m , for raising said rack as soon as the weight of the occupant of the chair is removed from the arm e , substantially as herein shown and described.

GEORG BERNHARD ULRICHS.
